UNITED STATES PATENT OFFICE.

SNOWDEN B. REDFIELD, OF EASTON, PENNSYLVANIA, ASSIGNOR TO INGERSOLL-RAND COMPANY, OF JERSEY CITY, NEW JERSEY, A CORPORATION OF NEW JERSEY.

LOCKING DEVICE.

Application filed March 31, 1926. Serial No. 98,823.

This invention relates to locking devices, but more particularly to a locking device for forming a connection between two members, such as pistons and the like, and in which the 5 members are intended to be arranged substantially coaxially with respect to each other.

The present invention is particularly applicable to compressors or engines of the 10 type in which differential pistons are employed and aims to permit relative transverse movement between two pistons, so that the pistons may adjust themselves in their respective cylinders when the diameters of 15 the pistons change due to variations in temperature and other causes of axial misalignment.

Another object is to prevent relative longitudinal movement between the various 20 portions which comprise the piston.

Other objects will be in part obvious and in part pointed out hereinafter.

The invention consists of the combination 25 of elements and arrangement of parts substantially as hereinafter described and more particularly pointed out in the appended claims and illustrated in the accompanying drawings, in which—

Figure 1 is an elevation in section of a 30 portion of an air compressor having a differential piston and in which the portions comprising the piston are held together by a locking device constructed in accordance with the practice of the invention,

Figure 2 is an enlarged detail view partly 35 in section illustrating more clearly the manner in which the pistons are locked together,

Figure 3 is a perspective view of the piston rod nut,

Figure 4 is a perspective view of the piston 40 rod lock nut,

Figure 5 is a perspective view showing a modification of a piston rod lock nut,

Figure 6 is a view in section taken through 45 Figure 5 on the line 6—6 looking in the direction of the arrows,

Figure 7 is a perspective view of a modified form of piston rod lock nut,

Figure 8 is a view in section taken through 50 Figure 7 on the line 8—8 looking in the direction of the arrows,

Figure 9 is a perspective view of a modified form of piston rod nut,

Figure 10 is a view in section taken

through Figure 9 on the line 10—10 looking 55 in the direction of the arrows,

Figure 11 is a perspective view illustrating another modification of the piston rod nut, and

Figure 12 is a view in section taken 60 through Figure 11 on the line 12—12 looking in the direction of the arrows.

Referring to the drawings, the invention is shown embodied in a compressor designated generally by A and having a cylinder 65 B in which is arranged a reciprocatory piston C. The piston C is of the double acting type and divides the cylinder B into a low pressure chamber D and an intermediate pressure chamber E. In the present instance 70 the piston C carries at its rearward end a skirt F which cooperates slidably with a bore G formed in the cylinder B for guiding the piston C and also to form a head for the intermediate pressure chamber E. 75

Secured to the end of the cylinder B is a cylinder H which in this instance comprises the high pressure cylinder of the unit and carries at its forward end a head J in which are arranged suitable inlet and exhaust valves K and L. In like manner, inlet valves K and exhaust valves L are provided for the low pressure and intermediate pressure chambers. In the drawings only one inlet valve and one exhaust valve is 85 shown for each of the cylinder chambers, but it is to be understood that this showing is merely made for illustrative purposes and that any suitable number of valves of either type may be provided for the various cylinder chambers. The cylinder chambers are 90 of course adapted to be connected to each other by suitable conduits (not shown) as is customary in machines of this type, but since the parts so far described, other than 95 the piston C, form no part of the present invention, further description thereof is considered unnecessary.

In accordance with the practice of the invention, a recess O is formed in the low pressure end of the piston C and into the bottom of this recess is arranged a wearing plate P which forms a seat for a flange Q carried by a piston rod R. The piston rod R acts as a support for a piston S which reciprocates in the cylinder H and is held against longitudinal movement on the piston rod R by a suitable nut T screwed on the outer 100 105

end of the said piston rod. Formed between the flange Q and the piston rod R is a cylindrical portion U of somewhat greater diameter than the piston rod R but of smaller 5 diameter than the flange Q and about which may be arranged a piston rod nut V threaded on its perimetric surface to cooperate with a threaded portion W at the outer end of the recess O. The piston rod nut V is 10 adapted to seat on a shoulder X formed in the recess and cooperates with an end of the flange Q for preventing longitudinal movement of the flange in the recess O. The bore Y in the piston rod nut V is preferably 15 of somewhat larger diameter than the portions U of the piston rod R so that the rod R is free to move transversely within limits without contacting with said nut. Similarly, the recess O is of slightly greater 20 diameter than the flange Q so that if the cylinder chambers D and H, in which the pistons C and S respectively are adapted to reciprocate, are not formed absolutely concentric with each other, the pistons may adjust 25 themselves in their respective cylinders without causing undue friction between the contacting surfaces of the parts which comprise the reciprocatory element of the machine. Although the flange Q of the piston rod R is 30 illustrated as being in line to line contact with the wearing plate P, it is to be noted that sufficient clearance is allowed between these members to permit of free transverse movement of the flange Q in the recess O. 35 In order that relative movement of the piston S and the rod R upon which it is mounted may be prevented, a pin Z or other similar locking device may be inserted into the portion U of the rod to cooperate with 40 a slot b formed in the end of the piston S. This forms a simple means for preventing rotation between the piston and the rod when assembling these parts.

Frequently in devices of this character 45 considerable difficulty is experienced in preventing unloosening of the piston rod nut or other equivalent means used for holding the pistons together. To overcome this 50 tendency in the present instance a lock nut c of substantially the same diameter as the piston rod nut V is screwed into the threaded recess W to bear at its inner portion against a flat portion d formed on the piston rod nut V. The flat portion d comprises 55 only a relatively small area at one end of the piston rod nut V and in this instance the piston rod nut V is tapered from the flat portion d in the direction of the threaded portion of the nut so that when the lock nut c is screwed in position in the recess W only 60 a small contact will exist between the piston rod nut V and the lock nut c.

To the end that the lock nut c may be 65 somewhat distorted within the threaded recess W for the purpose of preventing acci-

dental unscrewing of the lock nut, a series of slots e are cut in an end face of the lock nut c. The slots e may be of any suitable number, four being shown for illustrative purposes. Cutting the slots e in the lock 70 nut c has the effect of reducing the section of the lock nut so that when the pressure is applied to the lock nut for screwing it into the recess W, the threaded or outer portion of the nut is drawn out of the plane of the 75 central portion of the lock nut, thus producing a binding effect between the threads of the lock nut and those of the threaded recess W. The slots e also provide a convenient 80 means for the insertion of a wrench or other suitable instrument whereby the lock nut may be manipulated. The piston rod nut V is also provided with suitable slots f for the reception of a wrench for screwing the said 85 nut into and out of the recess W.

In assembling the pistons, the wearing plate P may be seated in the bottom of the recess O. The piston rod R may then be placed in the recess and the piston rod nut V screwed firmly against the shoulder X. 90 Thereafter the lock nut c may be screwed into the recess W against the flat portion d of the piston rod nut V. Continued turning of the lock nut c in the direction required for turning it into the recess will draw the 95 outer portion of the lock nut in the direction of the nut V and cause said lock nut to bind in the manner described. With the nuts V and c in position, the piston S may be mounted on the piston rod R so that the 100 slot b in the piston S engages the pin Z. The nut T may then be screwed into position on the rod R and the piston thus assembled will be ready for insertion into the 105 cylinders of the machine.

The advantages of this invention reside chiefly in the fact that two members, such as the pistons C and S, may be securely locked together and that the securing means thus employed will at all times prevent any 110 relative longitudinal movement between the pistons, while at the same time permitting relative transverse adjustment to compensate for any slight eccentricity of the cylinders which may occur during the machining of the parts, or for any unequal expansion or contraction of the walls of the several cylinders during the operation of the compressor.

Referring now to Figures 5 and 6, a lock 120 nut g is shown having L-shaped slots h which divide the lock nut into segments connected by small ribs j. The ribs j serve to render the nut g flexible so that when the nut is drawn firmly against the piston rod 125 nut V, the threaded portion of the lock nut g will be drawn out of alignment with the central portion of the lock nut and thus hold said lock nut firmly in placed position.

A further modification is illustrated in 130

Figures 7 and 8 in which longitudinal slots *k* are cut through the threaded portion of the lock nut *o* and an annular groove *p* is cut in one face of the lock nut, preferably 5 in line with the inner walls *q* of the slots *k*.

A modified form of piston rod nut is illustrated in Figures 9 and 10. In this instance one end of the piston rod nut *r* is provided with tapered surfaces *s* and *t* 10 which converge to form a prominence *u* against which the lock nut may be forced for the purpose of springing the lock nut to cause it to bind in the threaded recess *W*.

Figures 11 and 12 show another form of 15 piston rod nut in which one face of the piston rod nut *v* is spherical as at *w*. By thus forming the spherical face *w* on the nut, a single line of contact between the nut *w* and the lock nut will be assured, irrespective 20 of any distortion which may take place in the lock nut.

It is to be understood that I do not wish 25 to limit the invention to the precise showing in the drawings, but that the invention may be further modified in various particulars without departing from the spirit of the invention or the scope of the claims.

I claim:

1. In combination with a pair of coaxial 30 members, of a flange carried by one of the members, a recess in the other member to receive the flange, said recess having a threaded portion, a piston rod nut in the threaded portion cooperating with the flange 35 to prevent relative longitudinal movement between the members, and means screwed into the threaded portion for locking the piston rod nut in position, said means being flexible to permit its outer portion to be 40 drawn out of the plane of its central portion.

2. In combination with a pair of coaxial 45 members, of a flange carried by one of the members, a recess in the other member to receive the flange, said recess having a threaded portion, a piston rod nut in the threaded portion cooperating with the flange 50 to prevent relative longitudinal movement between the members, and a lock nut screwed into the threaded portion of the recess to bear against the end of the piston rod nut for preventing unscrewing of the said piston rod nut, said lock nut having reduced 55 portions to render it flexible and permit its outer portion to be drawn out of alignment with respect to its central portion.

3. In combination with a pair of coaxial members, of a flange carried by one of the members, a recess in the other member to receive the flange, said recess having a 60 threaded portion, a piston rod nut in the threaded portion cooperating with the flange to prevent relative longitudinal movement between the members, a flexible lock nut screwed into the threaded portion of the recess for preventing unscrewing of the said piston rod nut, and a shoulder on the piston rod nut bearing against the lock nut to distort the lock nut thus causing the threads of 65 the lock nut to bind on the threads of the recess for locking the lock nut against accidental removal.

4. In combination with a pair of cylindrical members, of a rod insertable into one 70 of the members, a flange on one end of the rod, a recess in the other member to receive the flange and permit transverse movement of the flange, said recess having a threaded portion, a piston rod nut screwed into the 75 threaded portion to cooperate with the flange for preventing longitudinal movement of the flange in the recess, a projection on the piston rod nut, and a lock nut screwed into the threaded portion to seat against the projection for preventing unscrewing of the 80 said piston rod nut, said lock nut having slots to permit distortion of the lock nut for locking said lock nut against accidental removal.

5. In combination with a pair of cylindrical members, of a rod insertable into one 85 of the members, a flange on one end of the rod, a recess in the other member to receive the flange and permit transverse movement of the flange, said recess having a threaded portion, a shoulder in the recess, a piston rod nut screwed into the threaded portion to seat on the shoulder for preventing longitudinal movement of the flange in the recess, a projection on the outer end of the 90 piston rod nut, and an externally threaded lock nut screwed into the threaded portion to bear against the projection for holding the piston rod nut against the shoulder, said lock nut having slots in one face to permit the externally threaded portion to be drawn 95 out of the plane of the central portion of the lock nut for preventing unscrewing of the lock nut.

In testimony whereof I have signed this 100 specification.

SNOWDEN B. REDFIELD.
